UNITED STATES PATENT OFFICE

108,444

DESIGN FOR A TRAFFIC MARKER

Joseph M. Huff, Oklahoma City, Okla.

Application January 27, 1937, Serial No. 67,307

Term of patent 3½ years

To all whom it may concern:

Be it known that I, Joseph M. Huff, a citizen of the United States, residing at Oklahoma City, in the county of Oklahoma and State of Oklahoma, have invented a new, original, and ornamental Design for a Traffic Marker, of which the following is a specification, reference being had to the accompanying drawing, forming part thereof.

I claim:—

The ornamental design for a traffic marker, as shown.

JOSEPH M. HUFF.
